METAL WORKING PRESS

Fredrich J. Rode, Chicago, Ill.

Application June 10, 1932. Serial No. 616,372

15 Claims. (Cl. 113—38)

This invention relates to improvements in metal working presses.

In presses of this character and as usually constructed, considerable difficulty has been experienced in that the ram or die slide when being lowered, and especially where the ram or slide is unevenly loaded with dies, will tilt or move out of its originally set position with respect to the work supporting surface.

10 Heretofore it has been proposed to overcome these objections by the use of one or more power shafts for reciprocating the ram or slide by connecting such shaft or shafts therewith in a manner that pressure will be exerted therefrom upon the ram or slide at spaced points on opposite sides of the center line intermediate and parallel with the front and rear edges of the ram; and also by means of the use of rock shafts, the centers of which are connected to crank throws 15

20 symmetrically arranged in opposite sides of the longitudinal center of the crank shaft.

While very good results have been obtained by the use of these constructions, they are more or less expensive, necessitating considerable space, 25 as well as providing a great number of parts which require considerable attention.

It is one of the objects of the present invention to improve and simplify the construction of presses of this character by eliminating such 30 complicated mechanisms and to provide means whereby the tendency of the ram or slide to tilt will itself be employed as a means for causing the ram or slide to aright itself, with the result that the lower or die carrying surface or 35 face of the slide will always be maintained in its originally set position with respect to the work supporting surface, in any position of the slide during the cycle of operation of the press, and against tilting, regardless of the position of 40 the die with respect to the slide, even though the slide is unevenly loaded with dies.

A further object is to provide an improved construction of this character which is applicable with equal efficiency in either a single or a double action press.

To the attainment of these ends and the accomplishment of other new and useful objects as will appear, the invention consists in the features of novelty in substantially the construction, 50 combination and arrangement of the several parts hereinafter more fully described and claimed and shown in the accompanying drawings illustrating this invention and in which

Figure 1 is a view in front elevation of a portion of a single action press of this character

constructed in accordance with the principles of this invention.

Figure 2 is a horizontal sectional view, with parts broken away, as taken on line 2—2, Figure 1.

Figure 3 is a detail sectional view taken on line 3—3, Figure 1.

Figure 4 is a view partly in elevation, partly in section, partly broken away and with parts omitted, of a double action press constructed 65 in accordance with the principles of this invention.

Figure 5 is a detail sectional view taken on line 5—5, Figure 4.

Referring more particularly to the drawings 70 and to the form of the invention shown in Figures 1 to 3, the numeral 10 designates generally the bed of the press upon which is mounted a die 11. Rising above the press bed are uprights 12 connected at their top by means of a crown 75 or head 13.

Journalized in the uprights 12 and extending across the space therebetween adjacent the crown is a shaft 14 provided with cranks 15 which are 80 connected by means of links 16 with a ram or slide 17 movable in guides or ways 18 secured to the uprights 12. Carried by the ram 17 is a die 19 which cooperates with the die 11.

The shaft 12 is driven from any suitable source 85 of power, not shown.

All of the above referred to parts are of the ordinary and well known construction.

In order to maintain the ram or slide 17 in its originally set position with relation to the surface of the bed 10 and against tilting movement 90 in the event that the ram or slide is unevenly loaded with dies, or in the event that the die 19 is not positioned exactly under the center of the ram 17, means are provided whereby any tendency of the ram or slide to tilt will be utilized as 95 a means for causing the ram or slide to aright itself and thereby prevent the same from so tilting. In carrying out this invention there is provided along the uprights 12, preferably along the guides 18, upright racks or spaced series of teeth 20, one of such racks being provided adjacent each corner of the ram 17.

Journalized in the ram or slide and extending across and adjacent each of the ends thereof is 105 a shaft 21, the ends of which terminate adjacent the front and rear faces of the ram or slide 17, and carried by each of these shafts 21 are gears 22 which are positioned adjacent and mesh with the racks 20. These shafts 22 may be arranged at any point intermediate the top and bottom of 110

the slide. The rack teeth as well as the teeth on the gears 22 are preferably of a substantial length.

- In the operation of the press it will be manifest 5 that the ram or slide will be reciprocated from the crank shaft 14 and as the gear 22 will roll over the racks 20 during such reciprocating movement, it will be manifest that the reciprocation of the ram will not be interfered with. 10 However, should there be any tendency of the ram or slide 17 to tilt or move out of its originally set position with respect to the supporting surface of the bed 10 of the press, by reason of the slide or ram being unevenly loaded with 15 dies, or if the die 19 is not properly set, it will be immediately overcome by reason of the fact that any pressure upon the ram or slide which tends to tilt the same will be manifested upon the racks and gears, and as these racks and gears are 20 always in mesh, such pressure which would tend to tilt the ram or slide will be immediately transferred through the gear and rack construction to the opposite side of the ram or slide, thereby causing the latter to aright itself so as 25 to maintain the ram or slide against tilting movement.

In the form of the invention shown in Figures 4 and 5, a double action press is illustrated and in which the ram or slide 23 which carries a work holder 24 is reciprocated in guides 25 carried by the uprights 26, by means of links 27 connected thereto through the medium of the adjustable screw connection 28 and which links are connected to a suitably operated crank shaft 29. 30 The slide 23 is hollow and reciprocable therein is another slide 30 to which a punch or die 31 is connected. This slide 30 is connected by means of links 32 to another crank shaft 33 suitably operated. The die or work holder 24 co-operates 35 with a die or work holder 34 secured to the bed 35 of the press. This die or work holder 34 encompasses a die 36 which latter co-operates with the die or punch 31.

The inner die or punch 30 is provided with 40 portions 37 which move in guideways 38 in the inner face of the outer slide 23 and arranged lengthwise of the guideways 38 are racks 39, the teeth of which are of a substantial length.

Carried by the slide 30 to extend across and 45 adjacent each end thereof, and journaled in suitable bearings is a shaft 40 which has secured to it and at each end thereof a gear 41. These gears 41 are arranged adjacent and mesh with the respective racks 39 so that during the movement of the slides 23-30, one with respect to the other, the gears 41 will roll over the racks 39 so as not to interfere with the relative movement 50 of these parts.

If, during the operation of the press and when 55 the slide 30 is depressed through the medium of the links 32, there is any tendency to cause the die 31 or slide 30 to tilt or move out of its originally set position with respect to the work supporting surface of the bed 35, such tendency 60 would be manifest upon the gears and racks 41-39 and as the gears and racks are always in mesh, this tendency will be immediately transferred from one side of the slide 30 to the other side thereof, with the result that it will operate 65 to cause the slide 30 and die 31 to aright themselves to overcome such tendency to tilt and thereby maintain the slide 30 against such tilting movement.

With both of the forms of the invention it will 70 be manifest that no matter where the pressure is

exerted upon the slide or at what point the tendency to tilt is manifested, such tendency will immediately serve as a force or power which is transferred to the opposite side of the slide and there operate to draw down or prevent this last 80 mentioned side of the slide from rising.

While the preferred forms of the invention have been herein shown and described. It is to be understood that various changes may be made in the details of construction and in the combination and arrangement of the several parts, within the scope of the claims, without departing 85 from the spirit of this invention.

What is claimed as new is:—

1. In a press, a frame, a reciprocable die slide 90 operable therein, a shaft operably mounted in the frame, a direct connection between the slide and the shaft, and means independent of the connecting means between the said shaft and slide and operating automatically whereby when pressure is exerted upon the slide on one side of the center thereof tending to tilt the slide, the portion of the slide on the other side of such center will be correspondingly moved and the slide will aright itself and will be maintained 95 against tilting.

2. In a press, a frame, a reciprocable die slide operable therein, a shaft operably mounted in the frame, means connecting the slide with the shaft, and means remote from the connection 105 between the shaft and slide and operating automatically when pressure is exerted upon the slide on one side of the center thereof tending to tilt the slide, the portion of the slide on the other side of such center will be correspondingly moved 110 and the slide will aright itself and will be maintained against tilting.

3. In a press, a frame, a reciprocable die slide operable therein, a shaft operably mounted in the frame, means directly connecting the slide 115 with the shaft whereby the latter will be reciprocated, and means disconnected from the slide reciprocating means and remote therefrom and operating automatically to maintain the slide against tilting during its movement under pressure regardless of the point or area at which 120 said pressure is applied to the slide.

4. In a press, a frame, a reciprocable die slide operable therein, a shaft operably mounted in the frame, means directly connecting the slide 125 with the shaft whereby the latter will be reciprocated, and positively operating means independent of the slide reciprocating means and operating automatically to maintain the slide against tilting during its movement under pressure regardless of the point or area at which 130 said pressure is applied to the slide.

5. In a press, a frame, a die slide reciprocable 135 therein, means for reciprocating the slide, and with respect to which the said reciprocating means is independent, operating automatically to neutralize any tendency of the slide to tilt during its movement under such pressure, regardless of the point or area of such slide at which such pressure is applied.

6. In a press, a frame, a driving shaft, a die slide reciprocable in the frame, a direct connection between the shaft and slide for reciprocating the latter, and gear and rack connections between said slide and a portion of the press 145 structure and operating automatically to neutralize any tendency of the slide to tilt during its movement under such pressure, regardless of the point or area of such slide at which such pressure is applied.

7. In a press, a frame, a die slide reciprocable therein, means for reciprocating the slide, and means other than said reciprocating means operating automatically to neutralize any tendency of the slide to tilt during its movement under such pressure, regardless of the point or area of such slide at which such pressure is applied, the second recited means embodying gear and rack connections between the slide and a stationary part of the press. 5
8. In a press, a frame, a die slide reciprocable therein, a shaft journaled in the frame, means connecting the slide with the shaft for reciprocation thereby, racks connected with stationary portions of the frame, and gears carried by the slide, meshing with and movable over the respective racks when the slide is reciprocated, said gears and racks operating to cause any pressure exerted upon the slide on one side of the center thereof to be distributed equally over the area of the slide for maintaining the slide against tilting. 10
9. In a press, a frame, a die slide reciprocable in the frame, a shaft journaled in the frame, connections between the slide and said shaft whereby the former will be reciprocated by the latter, upright racks secured to the frame adjacent the path of movement of the ends of the slide, and laterally spaced gears journaled at the ends of the slide and meshing with the respective said racks. 15
10. In a press, a frame, a die slide reciprocable in the frame, a shaft journaled in the frame, connections between the slide and said shaft whereby the former will be reciprocated by the latter, upright racks secured to the frame adjacent the path of movement of the ends of the slide, freely rotatable shafts journaled in the slide and extending across the same, and gears carried by the shafts and meshing with the said racks. 20
11. In a double action press a frame, a pair of telescoping slides reciprocable therein, shafts journaled in the press frame and individual to the slides, connections directly between the shafts and the respective slides for reciprocating them, and gear and rack connections between the said slides, one of the parts of each of the connections being carried by each of the slides and bodily reciprocable therewith. 25
12. In a double action press a frame, telescoping slides reciprocable therein, shafts journaled in the frame, connections directly between the shafts and the respective slides for reciprocating them, and means with respect to which the said shafts and the said connections are entirely independent, for automatically maintaining the slides against tilting one with respect to the other during their movement under pressure, regardless of the point or area at which such pressure is exerted upon the slides. 30
13. In a press frame, an inner and an outer slide capable of relative sliding movements, both co-operating with shaping dies, guiding surfaces between the slides, a driving shaft, a link connection between said shaft and said inner slide, and means other than said guiding surfaces operating to maintain the inner slide against tilting on an axis intersecting the axis of the driving shaft, regardless of the point or area at which pressure is exerted upon said inner slide. 35
14. In a metal working press, a driving shaft, a slide, a direct connection between said shaft and said slide and operating upon the slide to reciprocate the latter, and additional means independent of said connection and operating directly upon said slide to maintain the latter against tilting in a direction to intersect the axis of the driving shaft. 40
15. In a press, a frame, a die slide reciprocable therein, means for reciprocating the slide, and means entirely independent of the said reciprocating means, operating automatically to neutralize any tendency of the slide to tilt during its movement under such pressure regardless of the point or area of such slide at which such pressure is applied, the last recited means embodying an element rotatable about a fixed axis. 45
